DESIGN FOR A CONTAINER FOR POWDERED SOAP OR SIMILAR ARTICLE

Frieda Barnes, Cleveland, Ohio

Application September 15, 1947, Serial No. 141,403

Term of patent 7 years

(Cl. D58—8)

To all whom it may concern:

Be it known that I, Frieda Barnes, a citizen of the United States, residing in the city of Cleveland, county of Cuyahoga, and State of Ohio, have invented a new, original, and ornamental Design for a Container for Powdered Soap or Similar Article, of which the following is a specification, reference being had to the accompanying drawing, forming a part thereof.

Figure 1 is a front elevation of a container for powdered soap or similar article showing my new design;

I claim:

The ornamental design for a container for powdered soap or similar article, substantially as shown.

FRIEDA BARNES.
